UNITED STATES PATENT OFFICE.

FRED A. LANGHERST, OF WEXFORD, PENNSYLVANIA.

FLUID AND GAS TRAP.

Application filed January 23, 1928. Serial No. 248,857.

By way of illustration it might be stated that in oil wells wherein a packer is used to exclude water from the bottom of the well, the gas collects between the bottom of the well and packer to shut off the flow of oil to the well, thereby cutting down production and eventually spoiling the well.

It is therefore the object of the present invention to provide a gas relief device which may be operated to release gas at the bottom of the well to reduce pressure and insure a capacity flow of oil.

Another object of the invention is to provide means on the pump rod for contacting with the relief device to operate the relief device for releasing the gas.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a longitudinal sectional view through a well casing, the well tubing with which the device is used, being shown in elevation.

Figure 2 is a longitudinal sectional view through the gas trap.

Figure 3 is a fragmental sectional view illustrating a modified form of valve.

Referring to the drawing in detail, the reference character 5 designates a well casing which is of the usual and well known construction, and in which is positioned the well tubing 6.

The relief valve forming the essence of the invention is used in connection with oil or gas wells wherein a packer is employed for preventing the flow of water into the bottom of the well, the packer being indicated by the reference character 7 and surrounds the well tubing 6 and closely engages the well casing 5.

The reference character 8 indicates a length of tubing formed with threaded extremities to be connected with the well tubing as by means of the sleeves 9. Formed within the section 8 is a valve seat 10 against which the valve 11 seats, and normally rests, the valve 11 being tapered to closely fit the seat.

At the upper end of the valve 11 is a reduced portion 12 threaded to receive the lower internal threads of the tubular body portion 13 of the trap. At the upper end 60 of the body portion 13 is a head 14 formed with a flange that cooperates with the upper end of the tubular body portion to clamp the washer 15 therebetween.

Openings 16 are formed in the head while 65 similar openings 17 are formed in the valve 11, which openings permit the passage of oil upwardly through the trap during the pumping operation, and at the same time provide passageways to permit a portion of 70 the gas to pass through the trap, when the valve is elevated. Formed in the section 8 are bores 18 through which the gas may enter the interior of the tube 6 from where it passes upwardly and exhausts at the top 75 of the tubing.

As clearly shown by Figure 2 of the drawing, the pump rod which is indicated by the reference character 19 passes through the valve 11 and head 14, the head and valve 80 being provided with bores greater in diameter than the pump rod providing passageways through which gas may pass upwardly through the valve.

Formed on the pump rod at a point in 85 spaced relation with the valve 11 are laterally extended lugs 20, while at a point above the head 14 are laterally extended lugs 21, the lugs 20 being designed to contact with the valve 11 when the pump rod is moved 90 upwardly a predetermined distance, to lift the valve 11 from its seat uncovering bores 18, so that gas may pass upwardly around the valve and through openings 17 entering the interior of the valve.

In the form of the invention as shown by Figure 3 the removable tubular section is indicated by the reference character 8' and is formed with bores 18' having their inner ends extended through the valve seat indicated at 10'. The valve in this form and which is indicated by the reference character 11' is formed with a plurality of vertical bores 17' through which oil passes while the pump is in motion.

The pump rod which is indicated at 19' is provided with lateral lugs 20' which are adapted to engage the valve 11' to lift the valve off its seat so that gas may pass through bores 18' and upwardly around the 110 valve 11' to exhaust through the top of the tubing in which the trap is positioned. It

2
is of course understood that similar lugs are provided above the valve so that the rod 19' may be moved downwardly to force the valve to its seat.

6 The movement of the pump rod beyond the limits of its normal pumping stroke, to accomplish the operation of the relief valve, is imparted to the pump rod through the adjusting screw 22, which has connection with the upper end of the pump rod and with the beam 23, to the end that slight movement of the adjusting screw will tend to seat or unseat the valve to release the gas or return the valve to its seat.

11 I claim:

1. In combination with the well tubing and sucker rod of an oil well, a tubing section having an inclined valve seat formed inferiorly thereof and having a plurality of openings extending to the valve seat, a relief valve including a vertically movable elongated member, the lower end of the relief valve having bores normally registering

with the interior of the tubing in which the valve is positioned, means on the sucker rod 25 for engaging the valve to move the valve from its seat, and means on the sucker rod for returning the valve to its seat.

2. In combination with the well tubing and sucker rod of an oil well, a tube section 30 having bores extending therethrough and having a valve seat formed interiorly thereof, a vertically movable valve having bores at its lower end and bores at its upper end, said valve adapted to normally close the 35 bores of the tube section, means on the sucker rod for engaging the lower end of the valve to elevate the valve and permit gas to pass through the bores thereof, and means on the sucker rod and engaging the upper end of 40 the valve for moving the valve downwardly on its seat.

16 In testimony that I claim the foregoing as my own, I have hereto affixed my signature.

FRED A. LANGHERST.
